G. E. BERTRAND

KEY HOLDER

Patented Sept. 1, 1925.

1,551,790

UNITED STATES PATENT OFFICE.

GEORGE EUGENE BERTRAND, OF MINNEAPOLIS, MINNESOTA.

KEY HOLDER.

Application filed March 30, 1922, Serial No. 548,083. Renewed October 31, 1924.

To all whom it may concern:

Be it known that I, GEORGE EUGENE BERTRAND, a citizen of the United States, residing in Minneapolis, in the county of Hennepin and State of Minnesota, have invented a new and useful Key Holder, of which the following is a specification.

My invention relates to improvements in key-ring holders of the type set out in my co-pending application filed February 28, 1921, Serial Number 448,639.

Its object is to provide an improved device of this nature including a hook for detachably receiving a key-ring and a second hook for suspending the structure from the waist band, or other part of a wearer's clothing; also a flexible hood adapted to cover keys on a ring hung on said first hook, whereby said keys are prevented from injuring the clothing.

A further object is to provide a device of this kind, the parts thereof being capable of being quickly and easily assembled and adapted, when assembled, to retain the desired relation of parts, one with respect to the other, under all conditions in use.

Another object is to provide an improvement including assembled metallic members and flexible hood therefor, said members being formed to reinforce and lend shape to the flexible hood.

An additional object is to provide an improved article of this kind that will remain secure against accidental removal from a wearer's clothing, without undue wear of the clothing.

Other novel features of the invention will appear from the detailed description thereof taken in connection with the accompanying drawings forming part of this specification.

In the drawings, Fig. 1 is a rear elevation of a device embodying my invention; Fig. 2 is a central, longitudinal, sectional view taken on the line 2—2 of Fig. 1; Fig. 3 is a transverse sectional view taken on the line 3—3 of Fig. 2; Fig. 4 is a perspective view, the front flap of the hood being turned aside to expose the key-ring hook and Fig. 5 is a plan of a blank from which the shank and one of the hooks are formed.

Referring to the drawings, A indicates the resilient metallic body and B the flexible hood carried by said body. Said body includes a shank 10 having lips 11 and 12 projecting longitudinally from the ends thereof, opposed shoulders 13 and lugs 14 project-

ing laterally from the sides thereof, eyes 15 and 16 offset, respectively, from the front and rear of the shank 10 (Fig. 2) and a lug or catch 17 struck from the shank 10, said lug having its free end turned slightly backward. The lip 11 is turned back upon the shank (Fig. 2) to form a yielding supporting hook 18, said shank 10 being preferably beaded, as at 19, to strengthen the hook 18. A hook member b, designed for application to the shank 10, is arranged on the side of said shank opposite the hook 18 and in reversed relation. This hook member b is formed from a strip of resilient metal bent to form parallel reaches 20 and 21, joined by a loop 22, the reach 20 being apertured, as at 23, at its free end, while the other reach 21 is bent to form a ring receiving hook 24 and a yielding ring-guard 25. In applying the hook member b to the shank 10, the free end of the reach 20 is passed through the eyes 15 and 16 on the shank 10 (Fig. 2), the aperture 23 in said reach being caught by the lug 17 on said shank.

The hood B comprises front and rear flaps joined at their upper ends by a seam 26, said latter flap comprising upper and lower sections 27 and 28 joined by a seam 29 to form a pocket 30 between the lapping portions of said sections. The front flap includes an upper section 31, reduced at its lower end to form a strap 32, which strap is provided at its free end with a locking tab 33. Said front flap also includes a lower section 34, attached at one side to a side of the rear flap section 28, said lower section 34 having a slit 35 therein to receive said locking tab 33. A central slot 36 is cut in the rear flap section 27 near the seam 26 and two adjacent parallel slots 37 are cut in said section beneath said first mentioned slot. The former slot 36 receives the lip 11 forming the hook 18 and the latter slots 37 receive the locking lip 12. The shoulders 13 or spreaders, as they may be termed, fit snugly within the top of the hood, reinforcing the same and lending shape thereto. Said shoulders 13 and locking lip 12, together with the lip 11, secure the hood B upon the body A. The lugs 14 are turned rearward, the tips thereof being turned outward to prevent cutting the flap section 27. These lugs form bulges 38 in said hood flap upon opposite sides of the lip 11, said bulges, together with the gripping bend 39 at the free extremity of said lip, providing irregular clamping surfaces,

between which the wearer's clothing is engaged. 40 indicates key retaining cleats or spacers of felt or other suitable material, said cleats being sewed or otherwise attached to the longitudinal margins of the rear flap section 28. A fastener member 41 on the cleat 40, opposite the junction of the flap sections 28 and 34 co-operates with a companion fastener member 42 on the flap section 34 in holding the hood closed upon keys therein.

The shank 10 and hook member 7, both stamped from sheet metal, are readily assembled as hereinbefore explained. These assembled parts are readily applied to the hood B as follows: After separating the front flap sections 31 and 34 by removing the locking tab 33 on the former from the slit 35 in the latter, the flap section 31 is lifted to permit the application of the body A to the hood B (see Fig. 2), said flap sections 31 and 34 being thereafter joined by replacing the locking tab 33 within the slit 35.

25 In use, the device is preferably carried on a user's waist band by catching the hook 18 thereover, the irregular gripping surfaces afforded by the bulges 38 and the turn 39 on said hook, serving to secure the device against accidental removal. In applying a key-ring, the front flap is turned to one side (Fig. 4) and the ring caught in the hook 24 by pressing the same downward and thus flexing the ring-guard 25 outward sufficiently to permit the passage of the ring between said guard and the reach 21 of the hook member 7. The device is usually carried in a place, wherein the user cannot be conveniently guided by sight in applying the ring. The front of the hook 24 affords a relatively long surface upon which a ring may be guided upward to the mouth of said hook. In removing a ring from the hook 24, the user's thumb is braced against the thumb-piece formed by the loop 22, whereupon the ring may be readily freed from the hook against the action of the yielding ring-guard 25, without disturbing the position of the device upon the waist band.

30 Changes in the specific form of my invention, as herein disclosed, may be made within the scope of what is claimed without departing from the spirit of my invention.

35 Having described my invention, what I claim as new and desire to protect by Letters Patent is:

1. In a device of the class described, a metallic body comprising reversed hooks, 60 one for attachment to a wearer's clothing and the other to receive a key-ring or other object, said second hook having a yielding ring-guard, a thumb rest opposed to said guard, a flexible hood having front and rear flaps covering said latter hook, and means

on the body for securing the hood thereto and lending permanent shape to the upper portion of said hood.

2. In a device of the class described, a metallic body comprising reversed hooks, 70 one for attachment to a wearer's clothing and the other to receive a key-ring or other object, a ring-guard for said second hook, a flexible hood having front and rear flaps covering said latter hook, and means on the body to secure the hood thereto and lend permanent shape to the upper portion thereof.

3. In a device of the class described, a metallic body including a shank with reversed hooks thereon, one for attachment to a wearer's clothing and the other to receive a key-ring or other object, a flexible hood having front and rear flaps covering said latter hook, said rear flap comprising a 85 protective, retaining pocket for the shank and means on the shank for securing the hood thereto and lending permanent shape to the upper portion of said hood.

4. In a device of the class described, a metallic body including a shank with reversed hooks thereon, one for attachment to a wearer's clothing and the other to receive a key-ring or other object, a flexible hood having front and rear flaps covering said 95 latter hook, said flaps being joined at the top, also at one side beneath the top, and means on the shank for securing the hood thereto.

5. In a device of the class described, a metallic body carrying reversed hooks, one for attachment to a wearer's clothing and the other to receive a key-ring or other object, a flexible hood having front and rear flaps covering said latter hook, object retaining cleats on the longitudinal margins 105 of said rear flap and means on the body for securing the hood thereto.

6. In a device of the class described, a metallic body carrying reversed hooks, one for attachment to a wearer's clothing and the other to receive a key-ring or other object, a flexible hood having front and rear flaps covering said latter hook, object retaining cleats on the longitudinal margins 110 of said rear flap, companion fastener members for the hood flaps, one member being attached to the front flap and the other to one of said cleats.

7. In a device of the class described, a metallic body supplied with reversed hooks, one for attachment to a wearer's clothing and the other to receive a key-ring or other object, a flexible hood carried on said body, said hood having front and rear flaps covering said latter hook, the front flap being separable medially to permit of the assembling of said body and hood.

8. In a device of the class described, a resilient metallic shank having a hook 130

- turned back therefrom for supporting the device, a second hook applied to said shank for removably receiving and securing a ring or other object, a hood having front and 5 rear flaps covering said shank, said hood having a slot at the top thereof through which said supporting hook is projected, means on said shank engaging the rear flap of the hood, and means at the upper end 10 of the shank engaging beneath the top of the hood and co-operating with said flap engaging means to secure the hood upon the shank, also to reinforce the top of the hood and lend permanent shape thereto, said flaps 15 being joined at one side beneath the top of the hood, the front flap being separable medially to permit the application of said shank.
9. In a device of the class described, a 20 resilient metallic shank having a hook turned back therefrom for supporting the device, a second hook on said shank for removably receiving a ring or other object, a hood having front and rear flaps covering 25 said shank, said hood having a slot at the top thereof through which said supporting hook is projected, means on said shank engaging the rear flap of the hood, and means at the upper end of the shank engaging 30 beneath the top of the hood and co-operating with said flap engaging means to secure the hood upon the shank, also to reinforce the top of the hood and lend permanent shape thereto.
- 35 10. In a device of the class described, a shank having a lip turned back from the top thereof to provide a supporting hook, said shank being formed with an upper eye, a lower eye and a latching lug beneath said 40 lower eye, said eyes being offset, respectively, from the front and rear of the shank and the lug turned back therefrom, a hook member formed from a strip of resilient metal bent to form front and back reaches, 45 also a loop joining said reaches and turned forwardly of the former, the back reach being threaded downward through said eyes from the front of the shank and apertured to receive said lug, the front reach being 50 bent upward upon itself to form a ring receiving hook and thence bent back to form

a ring guard at the mouth of the hook beneath the loop, said loop providing a thumb-piece for the user in releasing a ring from engagement with said ring guard. 55

11. In a device of the class described, a shank having a lip bent back from the top thereof to provide a supporting hook, said shank being formed with an upper eye, a lower eye and a latching lug beneath the 60 lower eye, said eyes being offset, respectively, from the front and rear of the shank and the lug turned back therefrom, a hook member formed from a strip of resilient metal bent to form front and back reaches, 65 the back reach being threaded downward through said eyes from the front of the shank and apertured to receive said lug, the front reach being bent upon itself to form a ring receiving hook and a guard at the 70 mouth of said hook.

12. In a device of the class described, a shank having a lip bent back therefrom to supply a supporting hook, and a hook member comprising two reaches, one reach there- 75 of having a threaded interlocking connection with said shank, the other reach being shaped to form a yielding ring retaining hook and a thumb-rest opposed thereto.

13. In a device of the class described, a shank having a lip bent back therefrom to supply a supporting hook, and a hook member comprising two reaches, one reach being secured to the shank and the other reach forming a hook with a ring guard at the 80 mouth thereof and a thumb-piece there- above.

14. In a device of the class described, a shank, a hook on said shank for attachment to a wearer's clothing, a key-ring hook, a 90 ring-guard for said hook and a thumb-rest projecting forwardly over said key-ring hook in opposition to said ring-guard, said key-ring hook, ring-guard and thumb-rest being integral, each with the other, and comprising a unitary hook member, said member being removably attachable to said shank. 95

In testimony whereof, I have signed my name to this specification.

GEORGE EUGENE BERTRAND.
